YARN TENSIONING FOR KNITTING MACHINES

Henry Janssen, Wyomissing, Pa., assignor to Textile Machine Works, Wyomissing, Pa., a corporation of Pennsylvania

Application May 24, 1937, Serial No. 144,365

15 Claims. (Cl. 66—146)

My invention relates to means for, and the method of, tensioning yarns, particularly between yarn feeding devices, such as snappers, and fabrics being knitted, as in full fashioned hosiery or straight knitting machines.

The feeding of yarn to the loop forming elements of a usual knitting machine is controlled by a snapper device which, after allowing the yarn to be freely fed to the knitting elements, is manipulated to take up the slack in the yarn between it and the fabric during loop forming movement of the machine. To aid the snapper in tensioning the yarn, a ring member is ordinarily provided, through which the yarn passes from the supply to the snapper. The ring hangs upon the yarn to apply a predetermined tension thereto, and, although a certain amount of slack is present, the ring maintains the yarn substantially taut between the supply and the snapper. This slack in the yarn varies during the manipulations of the snapper but the ring aids the snapper in holding the yarn taut between the snapper and the fabric.

If for any reason, such as variations in the yarn, vibrations of the machine or accidental slippage of the yarn through a snapper, a greater length of yarn is accumulated between the snapper and the fabric than can be taken up by the usual reverse movement of the snapper, loose end loops will be formed in the fabric.

Also, where a plurality of yarns are fed to the knitting elements in recurrent sequence, as in the three carrier ringless principle, each yarn, after being laid in one course, stands idle for two courses before again being fed to the knitting elements. With the yarn held in this manner and with the repeated manipulations of the snappers, yarn is accidentally drawn from the supply thereby allowing the rings to drop onto their respective support members, whereupon the tensioning action of the rings on the yarn between the yarn supply and the snappers is removed. The removal of this tension along with the excess yarn drawn from the supply while the carrier remains idle, increases the slack in the yarn to such a degree as to permit the idle threads to be accidentally caught by the end sinkers whereupon "pullers" are formed and defective fabric results. It is also apparent that each yarn, due to this excess slack, will be loosely fed to the knitting elements until such time when its ring is again raised to an effective position where it will be operative to apply tension to the yarn.

The usual ring tension structure, unless care-

fully attended, frequently becomes sticky because of the gum, oil or moisture collected thereby from the yarn passing therethrough, and consequently the ring eventually sticks to the supporting wire and in turn becomes ineffective insofar as any tensioning action is concerned. Obviously, when this occurs on the machines of the prior art, no means is available for compensating for the slack in the yarn other than the snapper itself which is ordinarily incapable of satisfactorily compensating for slack in the yarn occasioned in the aforesaid manner.

Furthermore, the operation of the ring tensioning device depends entirely upon gravitational forces for its operation and consequently the speed of operation is a constant which has at times been found to be too slow for proper operation in connection with the present day high speed machines.

It is an object of my invention to provide a mechanism of simple construction which will be economical to manufacture and efficient in operation, and which will satisfactorily overcome the deficiencies of prior art devices of this type.

Another object is to provide a yarn tensioning device which will be sufficiently sensitive to permit its use on high speed knitting machinery.

Still another object of my invention is to provide a yarn controlling device for applying tension to the yarn during yarn feeding and for holding the yarn taut during loop forming movements of the machine.

A further object is to provide a yarn feed device adapted to take up the slack in the yarn, from the yarn feed device to the needles of the machine, where the yarn is held for a plurality of courses while other yarns are being formed into courses as in the alternating three carrier principle mentioned.

With these and other objects in view which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

In the drawings:

Figure 1 is a cross sectional view taken through a full fashioned knitting machine, illustrating my invention and the associated yarn supply and yarn feeding means;

Fig. 2 is an elevational view showing the snap-

per structure of Fig. 1 in one of its extreme positions;

Fig. 3 is an elevational view illustrating in full size a yarn tensioning device constructed in accordance with the present invention;

Fig. 4 is a view similar to Fig. 3, showing an advanced operative position and with certain of the parts being broken away to more clearly illustrate the invention;

10 Fig. 5 is a view of the invention taken in the direction of the arrows 5—5, Fig. 3;

Fig. 6 is a view similar to Fig. 3 illustrating a modified form of the invention;

15 Fig. 7 is a sectional view of the device shown in Fig. 6, with the parts thereof being shown in different operative positions;

Fig. 8 is a sectional view taken substantially along the line 8—8, Fig. 6; and

20 Fig. 9 is a perspective view illustrating the relation of a plurality of the devices of the invention in association with three yarn carriers operating in recurrent sequence.

25 In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines", copyright 1920, and in the "Reading" Full Fashioned Knitting Machine Catalogues, copyright 1929 and 1935, published by the Textile Machine Works, Reading, Pennsylvania, and in a pamphlet entitled "Knitting Machine Lectures", published in 1935 by the Wyomissing Polytechnic Institute, Wyomissing, Penna.

30 Referring to the drawings, and particularly to Fig. 1, the framework of a full fashioned hosiery knitting machine comprises a frame member 10, a front beam 11, a back beam 12, and a center bed 15 disposed transversely to the frame member 10.

35 A sinker head 20, comprising sinkers 21 and dividers 22, is arranged to cooperate with a bank of needles 25, carried by a needle bar 26, in forming the loops of a stocking fabric indicated by dot-and-dash lines 23. The needle bar 26 is supported by an arm 27 secured to a shaft 28 which imparts a vertical movement to the needles. The mechanism for operating the shaft 28 and the presser mechanism which rocks the needles toward and from the sinker head 20 during the up and down movement thereof to effect the usual 40 loop forming movements of the needles, is of well known construction and is not herein illustrated.

45 A yarn 30 is fed to the needles 25 from a supply bobbin 31 in a yarn box 32, which box is supported by a gallows or yarn box supporting bracket 33 secured to the machine frame. The yarn 30 passes from the bobbin 31 through an eyelet 36 secured in the top of the yarn box, over stationary guide rods 37 to a moistening trough 38. From the moistening trough 38 the yarn passes 50 through a tension ring 41 which is slidably mounted on a guide member 42 fastened to the supporting bracket 33. A loop 40, formed at the bottom of the guide member 42, acts as a rest for, and controls the lowermost position of, the ring 41. The yarn 30 passes from the ring 41 through a snapper device 43, secured to a snapper shaft 44 by a screw 45, and around another guide rod 46 to a yarn guide finger 47 which is fixed to one of carrier rods 48 of the machine. The carrier rods are separately slidably mounted in individual

bearings of a bracket 51 secured to the center bed 15.

5 Oscillatory movement is imparted to the snappers in timed relation to the needles 25 through a lever 52 having one end secured to the snapper shaft 44 and connected at its other end to a rod 53. The rod 53 is connected to a cam lever 56 which is pivotally mounted by a pin 58 on a bracket 57 secured to the back beam 12. The lever 56 has a follower 61 which is operated either by the regular knitting cam 62 or by the narrowing cam 63 depending upon the axial position of a cam shaft 64 on which they are secured; the follower 61 being biased toward the cams by a spring 66, one end of which is connected to the lever 56 and the other end to a shaft 67.

10 In producing a course of loops, the yarn is drawn from the supply bobbin 31, through the moistening trough 38, the ring 41, the snapper device 43 and the yarn guide finger 47, and is fed to the needles 25. As the yarn passes through the snapper device, the latter is operated so as to permit free movement of the yarn therethrough under the control of the low portion 62a of the cam 62; and at the end of the carrier travel, after the yarn has been fed to the full complement of needles, the snapper is raised from the position indicated in Fig. 4 to a point approximately midway between the positions indicated in Figs. 3 and 2 as controlled by the portion 62b of cam 62, whereupon the yarn again becomes anchored thereto and is drawn tightly around the last sinker 21 to which the yarn has been fed. As the needles move downwardly to draw the new course of loops through the previously formed course of loops, the snapper while continuing to hold the yarn also moves downwardly from the intermediate position to the position of Fig. 3 controlled by the portion 62c of the cam 62, at which time the needles have reached their lowermost cyclic position. During the subsequent return of the needles to the highest position in their operative cycle, the snappers also move to their uppermost position shown in Fig. 2 under the influence of the high cam portion 62d of the cam 62. Following this movement the roller 61 coacts with the low portion 62a of cam 62 to position the snapper as shown in Fig. 4, corresponding to the couloring operation. Thus the thread tension mechanism under the control of the cam 62 operates to maintain a desired degree of tension 15 on that portion of the yarn extending between the snapper 43 and the stocking fabric 23 during the knitting cycle of the machine; whereas the cam 63 becomes aligned with the follower 61 and controls the operation of this mechanism when the 20 machine operates through its narrowing cycle.

25 The snapper device 43, see Figs. 2, 3, 4 and 5, is provided with an eyelet 68, in one arm 71 of a snapper base or frame 72 mounted on the shaft 44. A second arm 73, also a part of the frame 72, has 30 a forked free end, the prongs 74 and 75 of which carry eyelets 77 and 80, respectively, through which the yarn passes from the eyelet 68 in its path to the yarn guide finger 47. The arm 71 has a leaf spring 78 secured thereto, as by screws 35 81, which has an opening 79 adapted to receive the eyelet 77, thereby permitting the spring 78 to press the yarn against the top of arm 73 and hold that portion of the yarn taut which extends from the snapper through the yarn guide finger 70 47 to the fabric being knit. The spring 78 cooperates with a fixed rod 81 in the manner illustrated in Fig. 4 to release the yarn as the latter is fed to the needles of the machine during the usual couloring operation.

Preparatory to feeding the yarn 30 from the yarn supply 31, through the snapper to the needles 25, the snapper is moved in a clockwise direction, by action of the normal knitting cam 62, the snapper shaft 44, and the intermediate linkage, from the position shown in Fig. 2, to the position of Fig. 4, the snapper moving away from the spring 78 to permit the yarn to pass freely through the snapper. Upon completion 10 of the couloring after the desired length of yarn has been fed to the needles, the snapper shaft 44 moves the snapper 43 in a counterclockwise direction to the aforesaid intermediate position controlled by the cam portion 62b, whereupon 15 the spring 78 again anchors the yarn to the snapper and tensions the yarn between it and the fabric. This action is ordinarily sufficient to control the feeding of the proper lengths of yarn to the needles and then properly tension the yarn 20 between the snapper and the needles during the downward and upward travel of the needles coincident with the looping of the new loops through the old. However, certain uncontrollable conditions, such for instance as the vibration 25 of the machine, tend to cause the yarn between the snapper and the needles to become slack whereupon a loose selvage results.

To supplement the action of the snapper and prevent the slackening of the yarn a third arm 30 82 is provided on the snapper frame 72 having a leaf spring 83 secured thereto, as by a screw 88. The spring 83 extends upwardly through an opening 84 in the arm 73 and is provided at its upper end with an extension 85 which carries an 35 eyelet 86 through which the yarn is laced as it passes from the eyelet 77 to the eyelet 80, respectively, provided on the prongs 74 and 75 of the arm 73. During the feeding of the yarn from the supply to the needles 25, the extension 85 of 40 the arm 83 is drawn to a position between the arms 74 and 75 (Fig. 4). However, if for any reason such for instance as variations in the yarn or vibrations of the machine, a greater length of yarn is provided between the snapper 45 and the fabric than can be taken up by reverse movement of the snapper, such greater length will be automatically taken up by the action of the spring arm 83. Thus the yarn is always held taut between the snapper and the fabric.

50 Figs. 6, 7 and 8 show a snapper device 91 of modified form in which an arm 92 corresponding to the arm 73, is of hollow or channel section provided with a top wall portion 93 for covering an opening 94, the top wall 93 preventing accidental 55 entanglement of the yarn 30, with the upper end 85 of the spring 83 as the yarn passes from the guide eye 68 to the guide eye 77.

Fig. 9 illustrates the use of three snappers 43a, 43b and 43c, on a snapper shaft 44a, each of construction similar to that of the snapper 43. These snappers are used to control the feeding of separate yarns 30a, 30b and 30c from bobbins 31a, 31b and 31c, over tension rod 37a, through 60 a trough 38a and through rings 41a, 41b and 41c on guides 42a, 42b and 42c, and in turn feeding the yarns in recurrent sequence through yarn guide fingers 47a, 47b and 47c on yarn carrier bars 48a, 48b and 48c to needles 25a on a needle bar 26a.

70 In this generally outlined arrangement of parts for producing ringless hosiery, during each stroke of the friction rod, two of the yarn guide fingers, in the series composed of fingers 47a, 47b and 47c, 75 remain idle, one at each side of the knitting sec-

tion, while the third finger moves with the friction rod (not shown).

Also, during each stroke of the friction rod, the snapper shaft 44a is actuated to tilt all of the snappers 43a, 43b and 43c in unison, each from 5 a position corresponding to that of Fig. 2 to a position corresponding to that of Fig. 4.

However, since only one of the yarn guide fingers 47a, 47b and 47c is laying yarn during any one stroke of the friction rod, and the snappers 10 of the idle yarns, as well as that through which the yarn being laid is fed, are open as in Fig. 4, a slight amount of yarn is inadvertently fed through the inoperative snappers. Obviously when yarn is thus supplied to idle carriers, slack 15 is formed which, however, in the present construction is automatically taken up by the springs 83a, 83b or 83c as the case may be.

As indicated in Fig. 9, each of the springs 78a, 78b and 78c is bearing against the stationary rod 20 81a, parts of which are broken away in the figure for clearness of illustration, which position corresponds to the position of the snapper of Fig. 4, which is the position corresponding to the couloring operation.

25 At the same time, the yarn guide finger 47b is traveling toward the left of the machine (Fig. 9), drawing its yarn 30b, and the ring 41b is in its uppermost position. Also, at this time, the yarn guide finger 47a has just completed a 30 stroke of the right, but since it has now been idle since the departure of the finger 47b from its right hand position and its snapper is open, the ring 41a has descended part way. Further, at this time, the yarn guide finger 47c has been idle 35 for approximately one-and-one-half strokes of the friction rod, during which period its snapper has opened twice and closed once. These repeated operations of the inactive snapper unintentionally draw sufficient yarn from the supply to create enough slack to permit the ring 41c to rest on its support member 40c illustrated as a loop at the bottom of the double wire like guide 42c. Similar supports 40a and 40b are provided for the other tension rings. Thus, continued accidental feeding of yarn through the inactive snappers is compensated for by the action of the springs 83a, 83b and 83c, as the case may be, which consequently prevents the formation of free end loops.

50 When the guide 47b reaches the left end of its stroke, the guide 47c is released for a stroke to the right to draw its yarn 30c through the snapper and the ring 41c, and the above described cycle is repeated. Thus, a method of, 55 and means for, tensioning a single yarn, or a plurality of yarns in selective or recurrent sequence, are provided by which the yarn or yarns are severally or simultaneously held, advance movement is given to the holding means during 60 each yarn laying movement, release of the holding means is effected while one or more of the yarns are fed, holding of the yarn is again effected and the holding means moved backwardly, and a relaxing effect in the yarn is offset as by tensioning it or deflecting it by means constantly 65 tending to take up slack in the yarn.

Obviously a thread control device of this improved construction may be employed either independently of, or in combination with, a ring 70 tension arrangement with equal efficiency, inasmuch as the operation of the resilient slack compensator element is entirely independent of the auxiliary devices. The sensitivity, automatic operation and simple construction of this device 75

5 makes it particularly desirable for use on full
function efficiently regardless of the oil, water
and other disturbing elements which prevent sat-
isfactory operation of more complex units. In
10 like manner, the fact that the present arrange-
ment is spring operated, permits it to be employed
satisfactorily on modern machinery the high op-
erative speed of which frequently prevents the
15 use of gravity operated devices.

15 This improved mechanism, in addition to being
adapted for use on knitting machines operating
on the alternating carrier principle, may likewise
be employed effectively to overcome numerous
20 other problems, such for instance as are fre-
quently associated with the production of knitted
fabric made from high twist silk. The natural
tendency of high twist silk is to double itself into
25 snarls, which, if carried into the fabric, create
defective fabric. Obviously, snarls in the yarn
cannot be formed unless slack exists in the yarn,
and since this device effectively prevents slack-
ening of the yarn, it is apparent that defects in
30 fabric resulting from snarls will be effectively
eliminated.

30 This device is particularly effective in pre-
venting the formation of loose loops on the last
needle to which the yarn is fed in successive
courses, which loops may be at the selvage edge
35 of the fabric or at an intermediate point, such for
example as at the inner edge of a high splice heel
portion of a full fashioned stocking. Loose loops
of this nature are particularly noticeable as well
as undesirable at the jointure between normal
40 weight and reinforced portions of fabric, inas-
much as the loose floating loops which extend
from the fabric are readily snagged and formed
into pullers by any object coming in contact
therewith whereupon the fabric is correspondingly
45 damaged. Consequently, since this improved
device prevents the yarn from becoming slack,
loose floating loops of the kind described will be
eliminated, and the fabric produced will ob-
viously be of an appreciably better grade than
50 was hitherto possible.

50 The simple construction of the auxiliary yarn
tensioning or slack compensator member em-
bodied in this invention, permits the amount of
take-up to be varied, simply by bending the
resilient piece toward or away from the control
55 rod 44, as desired. Furthermore, it is manifest
that springs of different strengths may be inter-
changeably used in order to increase or decrease
the degree of tension associated with this ar-
rangement, as the case may be, without in any
way departing from the concepts of the invention.

55 Of course, the improvements specifically shown
and described by which I obtain the above results,
can be changed and modified in various ways,
without departing from the invention herein dis-
closed and hereinafter claimed.

I claim:

60 1. In a yarn tensioning unit for a knitting ma-
chine, the combination with mechanism includ-
ing a base carrying yarn holding and releasing
elements, said mechanism including said base and
said elements being movable in the yarn feeding
65 direction to release and provide for advance of
the yarn and movable in reverse direction to hold
and exert backward pull on the yarn, of means
carried by said base for tensioning the yarn be-
tween said base means and a fabric being knitted.

65 2. A yarn snapper comprising a support, a pair
of elements thereon by which the yarn is guid-
ed, means including a spring on the support for

engaging and releasing the yarn before it passes
said elements, and means on the support in-
cluding a spring for deflecting the yarn be-
tween said elements to take up slack in the yarn
between said engaging and releasing means and
an element to which the yarn is fed. 5

3. A yarn snapper comprising a support, a pair
of eyelets thereon through which the yarn passes,
means including a spring on the support for en-
gaging and releasing the yarn before it enters the
10 eyelets, and means including a spring and a
third eyelet through which the yarn passes at a
position between the eyes of said pair for de-
flecting the yarn and taking up slack thereon
15 between an element to which the yarn is fed and
said first means.

4. In a knitting machine snapper tensioning
device, the combination with a member through
which yarn is fed to a fabric being knitted, a
spring carried by said member for engaging and
20 releasing the yarn, and a stationary element,
movement of said member in the feeding direc-
tion of the yarn causing the spring to engage the
stationary element to lift the spring off the yarn
25 for feeding the yarn, reverse movement of said
member causing the spring to engage the yarn
and exert a backward pull on the yarn, of aux-
iliary means including a spring carried by said
member for taking up slack in the yarn between
30 said first spring and said fabric.

5. In a knitting machine, a snapper tensioning
device comprising a member through which yarn
is fed to a yarn carrier, a spring carried by said
member for engaging and releasing the yarn, a
stationary element, movement of said member
35 in the feeding direction of the yarn causing the
spring to engage the stationary element to lift
the spring off the yarn for feeding the yarn, re-
verse movement of said member causing the
40 spring to engage the yarn and exerting a back-
ward pull on the yarn, a tension ring for float-
ing position on the yarn between the snapper
and a yarn supply, and means including a spring
45 for tensioning the yarn between said first spring
and the carrier.

6. In a knitting machine, a snapper tensioning
device comprising a member through which yarn
is fed to a yarn carrier, a spring carried by said
member for engaging and releasing the yarn, a
stationary element, movement of said member
50 in the feeding direction of the yarn causing the
spring to engage the stationary element to lift
the spring off the yarn for feeding the yarn, re-
verse movement of said member causing the
55 spring to engage the yarn and exerting a back-
ward pull on the yarn, a tension ring for float-
ing position on the yarn between the snapper
and a yarn supply, and means including a spring
60 carried by said member for tensioning the yarn
between said first spring and the carrier.

7. A yarn snapper comprising a support for
pivotal movement about a horizontal axis, a
generally horizontal arm on the support of hol-
low cross section having a forked free end, yarn
guide elements carried by the prongs of the fork,
65 a laterally deflectable spring mounted on the
support and extending to a position adjacent to
said prongs, and a yarn guide element carried
by the spring for deflecting the yarn toward the
interior of said hollow section arm from a posi-
70 tion between the prongs.

8. A yarn snapper comprising a support for
pivotal movement about a horizontal axis, a
generally horizontal arm on the support of in-
verted substantially channel shape having a 75

forked free end, yarn guide elements carried by the prongs of the fork, a laterally deflectable spring mounted on the support and extending to a position adjacent to said prongs, and a yarn 5 guide element carried by the spring for deflecting the yarn toward the channel from a position between the prongs.

9. A yarn snapper comprising a body portion for mounting on a snapper shaft, a first arm on 10 said body, an eyelet on said first arm constituting the entrance of the yarn to the snapper, a second arm on the body having a forked end and an aperture in the arm between the body and said end, a pair of eyelets in the respective 15 prongs of the fork, the yarn passing through said entrance eyelet and said pair of eyelets, a spring mounted on said first arm for engaging the yarn over the first eyelet of the pair and responsive to movement of the snapper about 20 the axis of the snapper shaft for engaging a stationary element and releasing the yarn, a third arm on the body, a spring mounted on the third arm and extending into said aperture of the second arm, and a fourth eyelet through 25 which the yarn passes carried by the second spring for deflecting the yarn between the eyelets of said pair toward said aperture to take up slack between said first spring and an element to which the yarn is fed.

30 10. A yarn snapper comprising a body portion for mounting on a snapper shaft, a first arm on said body, an eyelet on said first arm constituting the entrance of the yarn to the snapper, a second arm on the body of hollow cross section 35 having upper and lower fork prongs at its free end, a pair of eyelets in the respective prongs of the fork, the yarn passing through said entrance eyelet and said pair of eyelets, a laterally deflectable spring mounted on said first arm for 40 engaging the yarn over the first eyelet of the pair and responsive to movement of the snapper shaft for engaging an element and releasing the yarn, a third arm on the body, a second laterally 45 deflectable spring mounted on the third arm and extending to position adjacent to said prongs, and a fourth eyelet carried by the second spring adjacent to the prongs for deflecting the yarn between the eyelets of said pair toward the interior of said hollow section arm to take up 50 slack between the first spring and a fabric being formed.

11. A yarn snapper comprising a body portion for mounting on a snapper shaft, a first arm on 55 said body, an eyelet on said first arm constituting the entrance of the yarn to the snapper, a second arm on the body of inverted substantially channel shape having upper and lower fork prongs at its free end, a pair of eyelets in the respective prongs, the yarn passing through said entrance eyelet and said pair of eyelets, a laterally deflectable spring mounted on said first arm for engaging the yarn over the first eyelet of the pair and responsive to movement of the snapper shaft for engaging an element and releasing the yarn, a third arm on the body, a second laterally 60 deflectable spring mounted on the third arm and extending to position adjacent to said prongs, and a fourth eyelet carried by the

second spring adjacent to the prongs for deflecting the yarn between the prongs toward the channel to take up slack between the first spring and a fabric being formed.

12. The method of tensioning the yarns in a 5 machine for laying a plurality of yarns in which one of the yarns is idle during the laying of another yarn, which comprises the steps of simultaneously holding the yarns and moving the holding means of each yarn in the direction of feeding the yarns to release the yarns with each 10 yarn laying movement of the machine, simultaneously reversely moving the holding means of all of the yarns to hold and exert backward pull on all of the yarns at the end of each yarn laying 15 movement, and affecting each yarn between its holding means and a fabric being formed to offset a relaxing effect in the idle yarn caused by said movements thereof.

13. The method of tensioning the yarns in a 20 machine for laying a plurality of yarns in recurrent sequence, which comprises the steps of simultaneously holding the yarns and moving the holding means of each yarn in the feeding direction to release the yarns upon each yarn laying 25 movement of the machine, only one of the yarns being fed at each yarn laying movement, but all of the holding means acting as aforesaid and tending to simultaneously exert backward pull on all of the yarns at the end of each yarn laying 30 movement, and the step of deflecting each yarn between its holding means and a yarn laying element of the machine to exert a compensating tensioning effect to offset a relaxing effect caused by operation of the holding means on the inactive yarns.

14. A yarn tension snapper unit comprising a rockable base, a yarn guide on the base, a spring on the base responsive to rocking of the base for disengaging the spring from, and engaging the spring to, a stationary member to hold the yarn against, and to release the yarn from, said yarn guide, respectively, a second yarn guide on the base spaced from said first yarn guide in the direction of yarn feed, a spring mounted 40 on said base, and a third yarn guide carried by said second spring movable relative to said base for exerting tensioning forces on the yarn at positions on the yarn after the yarn passes said first guide and before the yarn passes said second guide.

15. A yarn tension snapper unit comprising a rockable base, a yarn guide on the base, an element movably mounted on the base responsive to rocking of the base for disengaging said element from, and engaging said element to, a stationary member to hold the yarn against, and to release the yarn from, said yarn guide, respectively, a second yarn guide on the base spaced from said first yarn guide in the direction of yarn feed, and means including a third yarn guide carried by, and movable relative to, said base for exerting tensioning forces on the yarn at positions on the yarn after the yarn passes said first guide and before the yarn passes said second guide.

HENRY JANSSEN.
